UNITED STATES PATENT OFFICE.

PHILIP HERZOG, OF MINNEAPOLIS, MINNESOTA.

BOLT-OPERATING MECHANISM.

SPECIFICATION forming part of Letters Patent No. 319,488, dated June 9, 1885.

Application filed January 31, 1885. (No model.)

To all whom it may concern:

Be it known that I, PHILIP HERZOG, a citizen of the United States, and a resident of Minneapolis, in the county of Hennepin and State 5 of Minnesota, have invented certain new and useful Improvements in Jail-Door Bolt-Operating Mechanism, of which the following is a specification.

In the drawings, Figure 1 is a sectional view 10 of a two-cell jail, showing my improved bolt mechanism arranged upon the doors of two cells. Fig. 2 is an enlarged detail of a portion of a jail-door and the surrounding walls of a cell and vestibule or corridor with my improved bolt mechanism attached thereto. Fig. 15 3 is a view of a portion of the side wall of a cell and vestibule or corridor, showing the positions of the bolt-operating levers, &c.

A represents the wall of the cell; B, the latticed walls of the prisoners' corridor; C, the outer walls of the prison; D, the jailer's corridor, and E' E' the latticed doors of the cells, all arranged in the ordinary manner. This represents one form of a small jail or prison; but 25 in some of the larger prisons the corridors may be arranged somewhat differently; but the arrangement shown is sufficient for the purpose of illustration, the mechanism being applicable to one cell, or to two or more cells 30 when placed in a row. Each of the cell-doors is hinged at a to the cells in the ordinary manner, and upon the side of each cell, on the opposite side of each door from the hinges a, are arranged bolts b' b', each door having 35 two bolts near its top and bottom. These bolts run back and forth beneath straps or staples d' d', riveted to the sides of the cells, and their inner ends are adapted, when pushed inward, to lap over the door-casings or enter 40 slots therein and lock the doors closed, and when pushed outward to release the doors.

F' is a long bar or rod supported in a horizontal position by straps or hangers e on the walls of the cell or cells above their doors, so 45 that the bar is free to be moved back and forth in a horizontal position.

F' F' are upright rods or bars, each attached at its upper end to the horizontal bar F', and running down and each connected to each of 50 the bolts b' b' of each cell-door, as shown.

F' F' are brace-bars, each connected by its upper end to the rod F', and running downward at an angle and connected to each of the rods F' between each pair of the bolts b' b', as shown. By this means the moving of the rod 55 F' back and forth will, by its being attached by the rods F' F' to the bolts b' b', move the latter back and forth with it and lock or unlock all the cell-doors connected to it at once. I have shown in Fig. 1 two cell-doors connected to the rod F'; but it is evident that any number from one to six or eight may be so connected. It is not generally advisable to arrange more than eight cells with one system of locking levers and bolts; but I do not wish 60 to be limited to any particular number. The rod F' runs out through one of the walls B of the prisoners' corridor into the jailer's corridor D, and is attached to one end of a small lever, H', the latter being in turn pivoted at 65 or near its center in a hanger, g', on the wall of the contiguous cell or corridor. The other end of the lever H' is pivoted in one end of a long lever, H'', the latter being in turn pivoted in a hanger, g'', on the wall of the cell or corridor, similar to the hanger g'. The lever H'' is provided on its lower end with a handle, i', and a slot adapted to fit over a staple or perforated bolt, i'', by which means the lever may be 70 operated and locked into its place, as shown in 75 Figs. 1 and 2. The pivot of the lever H'' is nearer the upper end than the lower end, so that an increase of power is obtained to operate the bar F'. Anti-friction rollers m (see Fig. 2) will be arranged in the hangers e of 80 85 the rod F', so the latter may be moved more easily. By this simple arrangement I gain several very important advantages. By means of the system of rods F' F' F', connected with the bolts on each cell, all the bolts of each cell are 90 opened and closed simultaneously, and without danger of cramping, as by means of the braces F' the bolts b' b' and rods F' F' move in an absolutely parallel line with the rod F'. Another important advantage is gained 95 by arranging the small auxiliary lever H' between the lever H'' and rod F', as the lower ends of the lever H' will be inward against the cell or corridor walls when the cells are locked, and not projecting outward and ob- 100

structing the corridor, as they would if they were attached directly to the bars F'. The levers H², after the cell-doors are opened, may be pushed in again to be out of the way, as no harm can result from the bolts b' b² being pushed in with the cell-doors open, so that the levers H² may be arranged so as not to obstruct the corridor either when the doors are open or closed.

10 I claim another advantage by attaching the brace-bars F³ to the bars F' at a point below the upper bolt, b', as I thereby not only gain a longer leverage and consequent increase of strength, but also support the lower bolt, b², and bar F² more thoroughly. By forming the small lever H' with its upper arm shorter than its lower arm a still greater leverage may be obtained.

Having thus described my invention, what
20 I claim as new is—

Cell-doors E' E², sliding bolts d' d² for each door, a common sliding bar, F', anti-friction rollers m m, upon which said bar slides, vertical rods F² F², connecting said bar F' with said bolts d' d², and diagonal brace-rod F³ F³, connecting said bar F' and vertical rods F² F², in combination with short lever H', the upper end of which is pivoted to said sliding bar F', and pivoted operating-lever H², having its short arm pivoted to lever H' and its long arm provided with a handle, substantially as set forth.

25 In testimony whereof I have hereunto set my hand in the presence of two subscribing witnesses.

PHILIP HERZOG.
